UNITED STATES PATENT OFFICE.

GEORGE W. CHRISTOPH, OF WAREHOUSE POINT, CONNECTICUT.

CARBURETING APPARATUS.

1,314,046.

Specification of Letters Patent. Patented Aug. 26, 1919.

Application filed January 31, 1917. Serial No. 145,819.

To all whom it may concern:

Be it known that I, GEORGE W. CHRISTOPH, a citizen of the United States of America, residing at Warehouse Point, in the county of Hartford and State of Connecticut, have invented certain new and useful Improvements in Carbureting Apparatus, of which the following is a specification.

This invention relates to improved carbureting means and more particularly to means for heating the constituents of the explosive mixture prior to carburation and for maintaining the carbureted mixture at a proper temperature until it has been delivered to the engine.

An object of the invention is to provide a carburetor wherein the fuel, air, or fuel mixture, or all three, or any combination thereof may be heated to and maintained at a predetermined temperature.

Another object of the invention is to provide a carburetor, wherein the fuel, air, and fuel mixture may be heated to and maintained at a predetermined temperature, and heat insulated means to convey the heated mixture to an engine without changing the temperature conditions thereof.

Other objects and advantages will appear in the following description and will be particularly pointed out in the appended claim.

The invention, in an illustrative embodiment, is shown in the accompanying drawings, in which—

Figure 1 is a sectional elevation of the carburetor;

Fig. 2 is an elevational view of an explosive engine showing the connections between the latter and the carburetor; and

Fig. 3 is a diagrammatical view of the electrical connections between the various elements shown in Fig. 1.

Referring to these drawings in detail and particularly to Fig. 1; reference numeral 5 designates the float chamber of the carburetor, which is supplied with fuel from an inlet pipe 6 and delivers fuel through an outlet pipe 7. Any of the well known means for governing the inflow of fuel into chamber 5 may be provided, as well as any other usual carburetor parts which may be found necessary or desirable. The mechanism within chamber 5 has not been illustrated since it is unnecessary to an understanding of the invention.

The pipe 7 extends from the float chamber 5 to a pipe 8, of somewhat larger diameter,

which supplies a canal 9 formed in the wall of the suction pipe 10 of the carburetor. The suction pipe 10, in the embodiment illustrated, is of elbow form and mounted vertically in the pipe is a suitable nozzle 11, which, as indicated in Fig. 1, is in communication with the described canal 9. The specific structure of the nozzle is immaterial to an understanding of the invention, and has not, therefore, been illustrated. Surrounding pipe 7 is an electrical heating coil 12 which may be of any suitable construction. For example, the coil may be embedded in a suitable insulating composition, indicated 70 conventionally by reference numeral 13, or the coil may be constructed in any other well known manner, as desired. The heating element 12 is adapted to heat and, if desired, to vaporize the fuel prior to its carburation 75 with the air, and, since the fuel may be changed from liquid to gaseous form before its admission into suction pipe 10, the pipe 8 and canal 9 have been shown somewhat larger than the pipe 7.

The heating element 12 is thermostatically controlled so that the temperature of the fuel may be maintained constant. Any suitable means may be provided to control the current passing through coil 12 in accordance with the temperature of the vaporized fuel. As an illustration of one operable means for accomplishing this result, the device shown in Fig. 1 may be used. A tube 14 closed at one end and filled with a suitable liquid, such as alcohol, for example, is connected to a gage 15 of any suitable type which is adapted for operation by the expansion of such liquid. The closed end of tube 14 is disposed within the canal 9 and, as indicated in Fig. 1, the tube may pass through a suitable stuffing box in the wall of pipe 10. The liquid within tube 14 expands under the heat of the vaporized fuel and its pressure actuates the pointer 16 of the gage in the well known manner. The tube 14 thus constitutes the sensitive element of the thermostat. An adjustable contact 17 is provided in the path of pointer 16 and the engagement of the latter with the contact closes an electrical circuit to control the heating element in a manner to be later described.

Suitably mounted near the inlet to pipe 10 is another electrical heating element 18 which may be constructed similarly to the element 12. Preferably the material within

- which the coil is embedded is formed with a plurality of radiating fins 19, since by so doing the air passing by the heating element 18 may be more rapidly and efficiently heated. Element 18 is also thermostatically controlled in a manner similar to that already described. A tube 20 depending into pipe 10 through the stuffing box shown constitutes the sensitive element for the thermostatic control of coil 18 in accordance with the temperature of the incoming air. This tube 20 is placed far enough from the heating coil so that it is not unduly influenced by it but is heated directly by the air after it has passed the heating coil. A gage 21, pointer 22, and adjustable contact 23 are provided as a thermostat for coil 18 in a manner analogous to that heretofore described.
- 20 The coil 12 is arranged (by suitably adjusting the contact 17) to heat the fuel to a predetermined temperature, and this temperature is maintained substantially constant by thermostatic control. The coil 18 is arranged to heat the air to a predetermined temperature which is also maintained substantially constant by similar means. The fuel, prior to carburation is heated to a temperature at which it is best vaporized and the air to a temperature at which it is best carbured with the vaporized fuel. The two constituents, therefore, mix under ideal conditions, and a thorough carburation of the constituents is obtained.
- 35 In order that the ideal temperature of the mixture thus obtained may be fixed or maintained until it has been drawn into the engine, the suction pipe 10, and the intake manifold 25 of engine 27 to which pipe 10 is connected as indicated in Fig. 2, are covered with suitable lagging 26, such as asbestos, for example, or any other suitable non-conductor of heat. This arrangement will overcome an external influence upon the carbureting system, such as, cold air which is normally blown across the intake manifold. To further insure the fixing and maintenance of proper temperature conditions for the mixture during its travel 40 through pipe 10 and manifold 25, one or more thermostatically controlled heating elements may be provided in these members. Thus, in Fig. 1, a heating element 28, similar to the element 18, is mounted centrally in pipe 10 at a distance above nozzle 11. A sensitive element 29 is connected to a gage 30, as heretofore described, and 31 and 32 indicate the pointed and adjustable contact member of the gage.
- 45 Referring now to Fig. 3, the electrical circuits for effecting the thermostatic control of the heating elements will now be described. One terminal of each heating element is connected to one terminal of a battery 35 or other suitable source of electro-

70 motive force. The other terminals of elements 12, 18, and 28 are connected to contacts 36, 37, and 38, respectively, and the other terminal of battery 35 is connected through a switch 39 to each of three contacts 40. Armatures 41, 42, and 43 normally close circuits through battery 35 (when switch 39 is closed) to the heating coils 12, 18, and 28 by connecting the contacts 36, 37, and 38, respectively, to the 75 contacts 40. Thus, the coils are normally energized and current continues to flow until the desired temperature of the medium heated by the coils has been reached. At such time, the pointers 15, 22, and 31 engage the contacts 17, 23, and 32 and close circuits to solenoids 45, 46, and 47, respectively, through a battery 48 or other suitable source of electrical energy.

80 Each pointer 31 is connected to one terminal of battery 48, and the other terminal of the latter is connected to one terminal of each of the solenoids. The other terminal of solenoids 45, 46, and 47 are connected to the contacts 17, 23, and 32, respectively. 85 The solenoids 45, 46, and 47 are arranged to lift the armatures 41, 42, and 43 and open the circuits to the heating elements 12, 18, and 28 until the pointers move away from their contacts. Thus, the fuel, air, and 90 carbured mixture may be heated to and maintained at the desired predetermined temperatures.

95 The operation of the carbureter will now be briefly described. Before starting the engine 27, the switch 39 is closed and the heating elements 12, 18, and 28 are energized. The fuel will be heated to the desired predetermined temperature, and this 100 temperature is made, by adjustment of the thermostat for coil 12, that at which it has been found by experiment that the fuel is best vaporized. Thus, as the engine is started, heated and vaporized fuel may be drawn through the nozzle as distinguished from 105 the cold liquid fuel obtained with the usual carbureter. The air drawn into pipe 10 is heated as it passes the element 18 to a temperature at which it has been found by experiment that it will be best carbured with 110 the fuel. The heated air and fuel mix above nozzle 11 to form the explosive mixture and the latter is, therefore, formed under ideal conditions. The mixture, thus obtained, is drawn to the engine through heat insulated 115 pipes so that the loss by radiation is minimized and the mixture is maintained at the desired temperature by heating elements in these pipes. One only of these elements for heating the mixture has been illustrated, 120 but it is to be understood that as many additional elements may be employed as is necessary to maintain the mixture at the proper temperature until it has been delivered to the engine.

The thermostats controlling the heating elements function to keep the mediums heated by the respective elements at the proper temperatures, and this result is obtained irrespective of weather conditions or other external influences. It is to be understood that the heating elements have sufficient capacity to heat the different constituents to the proper temperature under the most severe conditions. With less severe conditions, the heating elements will be energized intermittently, the energization being controlled thermostatically as described.

It will thus be seen that a carburetor has been provided wherein the fuel may be heated to a proper temperature for vaporization and the air may be heated to the proper temperature to secure the best results in the subsequent carburation with the vaporized fuel. Furthermore, the proper temperature of the ideal mixture thus obtained may be maintained so that the mixture is delivered in the desired condition to the engine. The present invention is characterized among other things in that automatic means are provided for independently controlling each heating element, so that each medium may

be kept constantly at the desired temperature.

The scope of the invention is pointed out in the appended claim.

What I claim is—

The combination with an engine, of an intake pipe therefor provided with an air inlet, means to supply fuel to said pipe, whereby fuel and air may mix to form an explosive mixture, means to heat the air to a predetermined temperature prior to its admixture with the fuel, means to heat the fuel to a predetermined temperature prior to its admixture with the air, whereby each constituent of the fuel mixture may be separately heated to that temperature best calculated to effect a proper mixture, means to independently control each heating means to maintain the respective mediums heated by the latter at substantially such predetermined temperatures, each of the heating means being capable of performing its function at all times, and means to maintain the mixture at a substantially constant temperature until it is delivered to the engine.

GEORGE W. CHRISTOPH.
